GOLF GAME BOARD OR SIMILAR ARTICLE

Barry R. Steiner and Ilane S. Steiner, both of 9115 Lamon, Skokie, Ill. 60076

Filed Apr. 24, 1967, Ser. No. 6,820

Term of patent 3½ years

(Cl. D34—5)

Fig. 1

Fig. 2

FIG. 1 is a plan view of a golf game board or similar article, showing our new design;

FIG. 2 is a front-top perspective view thereof, to the same scale.

The various barriers and pennants are shown in broken lines.

We claim:

The ornamental design for a golf game board or similar article, as shown and described.
